UNITED STATES PATENT OFFICE.

SAMUEL WEISSMAN AND RALPH WEISMAN, OF DETROIT, MICHIGAN.

SIDE THRUST SUPPORT FOR SPRING BED BOTTOMS.

Application filed January 29, 1923. Serial No. 615,523.

This invention relates to a side thrust support for spring bed bottoms and has special reference to that class of supports disclosed in our Patent No. 1,415,068, granted May 9, 5 1922, in which we show a conventional form of bed spring bottom having upper and lower frames with interposed springs and said frames are connected by means maintaining a defined relation between said 10 frames, particularly to limit the upward and inward movement of the marginal edges of the top frame relative to the lower frame. Such means is employed to prevent excessive pressure centrally of the spring bed bottom 15 from distorting the marginal edge of the top frame without materially interfering with the yielding of the springs in the usual manner. In other words, the top frame work or webbing of the spring bed bottom 20 is maintained stretched and taut without any central portion thereof being sagged or depressed due to constant use.

Our invention aims to provide side thrust supports each consisting of props, links or 25 members articulated to resist and limit the upward and inward movement of the top frame of the spring bed bottom, besides defining the lowering movement of the top frame should the marginal edges thereof be 30 depressed. This is accomplished by a simple, durable and inexpensive construction and since a plurality of supports are embodied in each spring bed bottom, any improvement which reduces the number of 35 support parts, standardizes such parts or simplifies the construction and manner of assembling the parts will produce a large saving when such spring bed bottoms are extensively manufactured.

40 Reference will now be had to the drawings, wherein—

Figure 1 is a diagrammatic plan of a 45 spring bed bottom in accordance with our invention;

Fig. 2 is a side elevation of a three link side thrust support;

Fig. 3 is a similar view of a two link side thrust support.

As illustrating a conventional form of 50 spring bed bottom, we show a lower frame 1 and the side rails 2 of this frame are connected by transverse spring supporting members 3 on which are mounted and suitably secured the lower convolutions of 55 springs 4, said springs having the upper convolutions thereof within an upper frame

6 which is held in spaced relation to the lower frame 1 by the springs 4. The spring supporting members 3 may be conveniently considered as being in sets with the members of each set connected by longitudinally disposed bars 7 and each bar, intermediate its ends, is connected to the rail 2 by an inclined base piece 8 having its ends bent or twisted for attachment to the rail 2 and the 65 bar 7 by rivet or other fastening means.

Reference will now be had to Fig. 2 wherein the inner end of the base piece 8 has a fixed and rigid upright 17 to which the inner end of the frame link 11 is connected, 70 by a pin and slot connection. The frame link 11 has its inner end longitudinally slotted, as at 23, to receive a stud or pin 24 of the upright 17, and the lower end 25 of said upright extends below the base piece 8. 75 Pivots connected to the intermediate portion of the frame link 11 is a connecting link 26 which is also pivotally connected to the base piece 8 with the lower end of the connecting link connected by a coiled retractile 80 spring 27 to the lower end 25 of the upright 17. An outstruck stop lug 28 of the frame link 11 defines the angular relation of the links 11 and 26.

In Fig. 3 the base piece 8 has a longitudinal slot 34 for a pin or stud 35 of the frame link 11 and said frame link has its intermediate portion pivotally connected to a link 36 similar to the link 26. The lower end of the link 36 is connected by a coiled retractile spring 37 to the lower edge of the base piece 8, which is cut away to provide clearance for said spring. The action of this last arrangement of links is somewhat similar to that shown in Fig. 2, with 95 the exception that the inner lower end of the frame link 11 is at all times held by the base piece 8 to shift longitudinally thereof.

In all of these forms of my invention the lower inner end of the base piece 8 may terminate in a tongue 38 clenched in an opening 39 of the bar 7.

While in the drawings there are illustrated the preferred embodiments of our invention, it is to be understood that the structural elements are susceptible to such changes as fall within the scope of the appended claims.

What we claim is:—

1. In a bed spring bottom wherein top 110 and bottom frames are held in superposed relation by springs between said frames;—

means for maintaining a defined relation between said frames, said means comprising units with each unit including a base piece, an inclined frame link having one end connected to the top frame of the bed spring bottom, a rigid upright on said base piece, a pin and slot connection between the upper end of said upright and the inner end of said frame link, and a connecting link supporting said frame link relative to said base piece.

2. A bed spring bottom as called for in claim 1, and a spring connecting said connecting link to the lower end of said upright.

3. In a bed spring bottom wherein top and bottom frames are held in superposed relation by springs between said frames; means for maintaining a defined relation between said frames, said means comprising units with each unit including a base piece, an inclined frame link having one end con-

nected to the top frame of the bed spring bottom, a connecting link pivotally connected to said inclined frame link and to said base piece with the lower end of said connecting link extending below said base piece, an upright on said base piece; a spring having one end thereof held from said base piece and the opposite end of said spring connected to the lower end of said connecting link so that the retractile force of said spring may cooperate with said connecting link in supporting said inclined frame link, and a pin and slot connection between said upright and said inclined frame link so that the inner end of said inclined frame link will have a defined and limited movement relative to said base piece.

In testimony whereof we affix our signatures.

SAMUEL WEISSMAN.
RALPH WEISMAN.
